(57) **CLAIM**

The ornamental design for utensil handle, as shown and described.

DESCRIPTION

FIG. 1 is a perspective view of utensil handle showing my new design;

FIG. 2 is a front elevational view of utensil handle of FIG. 1;

FIG. 3 is a rear elevational view of utensil handle of FIG. 1;

FIG. 4 is a left side view of utensil handle of FIG. 1;

FIG. 5 is a right side view of utensil handle of FIG. 1;

FIG. 6 is a top view of utensil handle of FIG. 1;

FIG. 7 is a bottom view thereof; and,

FIG. 8 is a perspective view showing the utensil handle applied to a teaspoon. The broken line showing of a teaspoon is for illustrative purposes only and forms no part of the claimed design.
